UNITED STATES PATENT OFFICE.

FRANK L. SESSIONS AND GEORGE B. NORRIS, OF COLUMBUS, OHIO,
ASSIGNORS TO JOSEPH A. JEFFREY, OF COLUMBUS, OHIO.

MINING-MACHINE.

SPECIFICATION forming part of Letters Patent No. 760,575, dated May 24, 1904.

Application filed January 6, 1903. Serial No. 138,044. (No model.)

To all whom it may concern:

Be it known that we, FRANK L. SESSIONS and GEORGE B. NORRIS, citizens of the United States, residing at Columbus, in the county of Franklin and State of Ohio, have invented certain new and useful Improvements in Mining-Machines, of which the following is a specification, reference being had therein to the accompanying drawings.

Figure 1 is a plan view of a mechanism embodying our improvements. Fig. 2 shows the lubricator and the parts to which it is attached. Fig. 3 is an end view of the lubricator. Fig. 4 is a side view, partly in section, of the lubricator. Fig. 5 is a plan view of the lubricator with the cover detached. Fig. 6 shows several of the details.

In the drawings we have selected for illustration a mining-machine of a form now well known, and inasmuch as many of the parts thereof do not enter into the essential features of the present invention they need not be here fully described in detail. As concerns the particular form of machine shown, reference may be made to the patent, No. 684,356, to H. B. Dierdorff, dated October 8, 1901. For present purposes it is sufficient to note that A indicates the bed-frame as a whole, and B the carriage, which moves forward and back on the bed. As illustrated, the bed has side bars α , with the rack-bars α' at the upper edges and with the cross-girths or bottom bars α'' .

The carriage-frame comprises the two parts β and β' , the former serving as a support for the motor, the shafting, and the gearing, while the latter constitutes the frame upon which the cutting-chain is supported and around which it travels. The motor-supporting part has connected with the motor a set of gear elements, which transmit the power to the cutter-chain, and also a set of shafts and gearing, which transmit some of the power to the carriage-feeding mechanism, the latter being indicated as a whole by D. As before said, the details of these parts will be readily understood upon reference to the aforesaid

patent. The forward part of the carriage comprises a central frame bar or bars at E, chain-guiding bars at F and F', and a cross-head at F''. G indicates the cutter-carrying chain. It is composed of cutter-links g and connecting-links g' . The chain is fitted to and travels around the frame, the side bars F F' and the cross-head F'' having a guideway 55 for the chain-links, which retains them in proper lines of travel and out from which the cutters project, the points of the latter traveling on the dotted line indicated by g^2 . The movement of the chain and of the cutter 60 around the guideway on the frame is effected by means of the sprocket-wheel at G' below the motor. The chain encounters great resistance as it travels around the guide, not only because of its engagement with the coal 65 through the cutter-points, but also because of its being confined in, resting upon, and bearing against the walls of the guideway. Constant lubrication is necessary in order to have the power supplied to the chain with sufficient 70 economy. Heretofore this lubrication of the chain has generally been accomplished by the operator from time to time pouring or dropping oil or lubricating material upon the chain-links at some point where they are exposed. In 75 the present instance the lubricating is effected by the device shown. This comprises two principal elements, one indicated as a whole by H and the other by I. At H there is a lubricator receptacle or vessel which is secured at 80 a suitable point to the traveling frame, preferably, as here shown, to the motor or to the motor-support. This vessel has a chamber J, capable of receiving and retaining a sufficiently large body of oil or lubricant. The 85 oil that escapes from this chamber is conducted by a guide J', the delivering end of which is directly over the chain at points near the driving sprocket-wheel. The oil is prevented from flowing from the chamber J by a controlling mechanism at K. This comprises a valve k , which normally closes the entrance-orifice to the guide J'. The valve part is formed at the end of a stem k' , which extends

upward and is held in a guide at L. The valve and valve-stem are normally held up in position for closing the port by means of a spring k'. When the valve is moved downward, the oil can pass around it into the spout or delivering-duct J', the dimensions of the latter in cross-section being somewhat larger than that of the valve, as shown at k'. The valve is intermittently moved downward to open the port at intervals, as follows: M is a vibrating finger or arm arranged to strike or press upon the upper end of the stem k'. As shown, it is secured to a rock-shaft or pin M', mounted in the wall of the lubricator vessel. At its outer end it carries an arm N. It indicates a stationary tripper secured to the bed-frame and lying in the path of the arm end as it moves forward with the carriage. There may be as many of these tripping devices I as are deemed necessary located at suitable intervals along the side part of the bed. When the machine is in operation and the carriage is under the action of the feeding mechanism moving forward, the rocking arm N contacts with one after the other of the trippers I, and while in such contact the finger M is pressed and held down against the stem k' and the latter is pushed down far enough to let some of the oil pass from the receptacle into the guide J'. From the latter it slowly drops upon the rapidly-moving chain-links just before they enter the guide F. As they move through the guideway the oil is distributed, and the guide-walls and the chain-pintles are kept properly lubricated. The valve is held open only for a brief period while the arm N is engaged with the tripper I. After escaping therefrom the valve is closed by the spring k', the arm N by its gravity returning the rock-shaft and the presser-arm M to their normal positions. We have shown a series of the tripper elements I; but it will be understood that they may be varied in number. Under some circumstances a single one will be sufficient. When the carriage is returning—that is, moving in the outward direction at the time the cutters are being withdrawn from the coal—the arm N may engage with the tripper I; but this will have no effect upon the valve, as the arm M will be moved away from the stem k', sufficient room being provided for it in the upper part of the box or reservoir, and the cover of the latter may be formed with a socket enlargement, as shown at O, to assure sufficient freedom of movement of the end of the part M.

What we claim is—

1. In a mining-machine, the combination with the carriage, the bed, and the cutter-carrying chain mounted upon the carriage, of the lubricant-receptacle, the valve, controlling the flow of oil therefrom, means for guiding the oil to the chain, and automatically-actuated tripping devices for intermittently open-

ing the valve as the carriage moves along the bed to permit a limited flow of oil, substantially as set forth. 65

2. In a mining-machine, the combination of the bed, the carriage moving forward and back on the bed, the cutter-chain on the carriage, the lubricant-receptacle on the carriage arranged to deliver oil to the chain, the valve controlling the flow of oil from the receptacle, means for holding the valve normally closed, the automatically and intermittently acting tripper, and means interposed between the tripper and the valve, and adapted to engage with the valve when the carriage is moving in one direction and to remain disengaged therefrom when it is moving in the opposite direction, substantially as set forth. 70 75

3. In a mining-machine, the combination of the bed, the carriage moving forward and back on the bed, the cutter-chain on the carriage, the lubricant-receptacle on the carriage arranged to deliver oil to the chain, the valve controlling the flow of oil from the receptacle, means for holding the valve normally closed, the automatically intermittently acting tripper, and the rocking arm M interposed between the tripper and the valve and arranged to be pressed in one direction by the tripper to open the valve when the carriage is moving in one direction, and to be pressed in the opposite direction by the tripper when the carriage is moving in the opposite direction, substantially as set forth. 80 85 90

4. In a mining-machine, the combination of the bed, the carriage moving forward and back thereon, the cutter-chain on the carriage, the lubricant-receptacle on the carriage arranged to deliver oil to the chain, and means for intermittently delivering oil from said lubricant-receptacle to the said chain, substantially as set forth. 100 105

5. In a mining-machine the combination of the bed, the carriage moving forward and back thereon, the cutter-chain on the carriage, the lubricant-receptacle on the carriage arranged to deliver oil to the chain, and means for intermittently delivering oil from said lubricant-receptacle to the chain as the carriage moves forward on the bed, substantially as set forth. 110

6. In a mining-machine, the combination of the bed, the carriage moving forward and back thereon, the cutter-chain on the carriage, the lubricant-receptacle on the carriage arranged to deliver oil to the chain and means arranged to deliver oil intermittently from said lubricant-receptacle when the carriage is moving in one direction and to remain inactive when the carriage is moving in the other direction, substantially as set forth. 115 120

7. In a mining-machine, the combination with the bed, the carriage moving forward and back thereon, and the cutter-chain on the carriage, of a lubricant-receptacle on the car-

riage arranged to deliver oil to the chain, the valve controlling the flow of oil from said receptacle, means for holding the valve normally closed, the tripping devices secured at 5 intervals along the bed and means interposed between said tripping devices and the valve adapted to engage with said tripping devices to operate the valve, substantially as set forth.

In testimony whereof we affix our signatures in presence of two witnesses.
